UNITED STATES PATENT OFFICE.

GEORGE R. PYPER, OF SALT LAKE CITY, UTAH, ASSIGNOR TO PYPER ANIMATED SIGN COMPANY, OF SALT LAKE CITY, UTAH, A CORPORATION OF UTAH.

ANIMATED SIGN.

1,382,229.

Specification of Letters Patent. Patented June 21, 1921.

Application filed June 30, 1920. Serial No. 392,955.

To all whom it may concern:

Be it known that I, GEORGE R. PYPER, a citizen of the United States, and a resident of Salt Lake City, in the county of Salt Lake 5 and State of Utah, have invented certain new and useful Improvements in Animated Signs, of which the following is a full, clear, and exact specification.

My invention is concerned with animated signs, and in one aspect it is concerned with a simple, cheaply constructed sign in which the subject matter can be readily renewed or replaced without dismantling the main portion of the sign. To this end I employ a 10 frame adapted to receive in suitable grooves or otherwise a cheap poster picture, which has been pasted upon or associated with an opaque screen plate made of metal or cardboard with a portion back of the portion of 15 the picture that is to be animated cut away. Back of this cut away portion I place in the frame a sheet of preferably metal, and preferably of the same size as the screen plate that has relatively small closely placed 20 perforations therein.

Back of the animated portion I place a powerful light, preferably a high candle power incandescent bulb with the incandescent portion of the filament occupying a 25 small space. Between the light and the animated part I introduce an animating member, such as a slotted disk, and provide means to rotate it at the proper speed so that the interruption of the illumination produces 30 the desired animating effect.

In another aspect it is concerned with a changeable animated sign in which the animated portion may for different subjects be located in different places on the face of the 35 sign, and it is designed to produce an animating member that may be readily positioned to coöperate with animated portions in different parts of the sign, and which may further be readily driven in any of its different positions.

In a final aspect, it is concerned with a novel method of and apparatus for producing an irregular animation, such for instance as is necessary to produce the appearance 40 of rising flames, which vary in height and are consequently irregular in their apparent movement. The fundamental feature of this portion of the invention is the employment of an animating screen, such as 45 a disk for instance, in which the different

apertures through which the light passes, or described conversely, the different screens which interrupt the light, are irregular and non-symmetrical, so that although the screen moves steadily between the light and the 60 part to be animated, the animating light is interrupted irregularly so that an irregular animating effect is produced.

To illustrate my invention, I annex hereto two sheets of drawings in which the same 65 reference characters are used to designate identical parts in all the figures of which—

Figure 1 is a front elevation of a sign embodying my invention;

Fig. 2 is a vertical section as seen on the 70 line 2—2 of Fig. 1;

Fig. 3 is an elevation as seen in section on the line 3—3 of Fig. 2, with a portion of two of the screen plates broken away to expose the animating disk back of them; 75 and

Fig. 4 is a section on the line 4—4 of Fig. 3.

I have designed my present invention more particularly for small cheap signs, in 80 which the subject matter can be changed at will without any great expense. To this end I have illustrated a box 10, constituting a permanent casing, which may be strongly constructed and which is preferably pro- 85 vided with a door 11 at the rear to give access thereto. At the front of the casing, I form an opening covering substantially the entire front, and bounded by the rectangular molding or strips 12, there preferably be-

ing an elongated aperture 13 at the top through which the various screen plates may be introduced. To form a guide for these screen plates, I place on the inside of the casing, preferably on both sides and the top 95 and bottom the inwardly projecting flange 14, which is parallel to the molding or strips 12 and coöperating therewith forms a channel on both sides and the bottom of the casing to furnish means for holding the three 100 screen plate members 15, 16 and 17 securely in place, while permitting of their ready removal and replacement. The front member 15, which is shown as of an exaggerated thickness, is preferably a full sized poster 105 sheet of comparatively thin and consequently transparent paper, which may have the matter thereon printed in any desired colors. Immediately back of the poster 15 is the member 16, which is preferably formed 110

of some comparatively stiff paper, or cardboard, which is opaque or substantially so, and in this sheet will be cut one or more apertures 18, which will be of the proper size, shape and location to register with the portion of the poster that is to be animated, such for instance as the flames indicated on the poster, which, as will be seen, represents a mantel with a grate and coal fire 10 therein from which the flames leap upward to the chimney, an appropriate subject, for instance, for advertising coal. Back of the member 16 is placed the member 17, which is preferably a sheet metal plate that is perforated all over its face with small, preferably regular and closely spaced perforations, such as are shown in Fig. 3. The illumination for the sign is furnished by the incandescent lamp 19, which is preferably 15 located just below and to one side of the flames, and which is shown as supported from the door 11, and it will be understood that this lamp is suitably wired and connected to the necessary current for operating the same. The perforations in the member 20 25 17 soften the effect and the member itself prevents the lamp 19 from being visible, although the perforations allow the passage of sufficient light to furnish the necessary illumination.

As I contemplate changing the subject matter of the posters, and consequently the location of the portions to be animated, I 30 preferably provide means for supporting the animating disk 20 so that it can be readily positioned to coöperate with any portion of the disk, and to this end I secure on one of the inner sides of the casing, the bracket 21, which has pivoted thereon the bar 22, which 35 can be secured in any desired adjustment by the wing nut 23 coöoperating with the bearing formed between the bracket 21 and the bar 22 in a well known manner to secure the bar rigidly to the bracket in any position of 40 adjustment. At the outer end of the bar 22 I pivot thereto another bar 24, and provide this joint also with a wing nut 25 so that this joint can be made rigid in any adjustment. On the lower end of the bar 24, as seen in 45 Fig. 22, I place the elongated bearing sleeve 25^a, in which is journaled shaft 26 having the animating disk 20 secured on its front end, and its rear end may be threaded and provided with a nut 27 by which the disk 50 20 is held from movement back and forth toward the front of the frame, but is free to rotate. With this mounting it will be obvious that the animating disk 20 can be adjusted adjacent to and so as to coöperate 55 with any portion of the screen, and in order that it may be readily driven in any adjustment, I preferably provide a small fan motor 28, driving the fan 29 and carried by bracket 30 which can be secured on the side 60 or top and bottom walls of the casing in

any desired position so as to coöperate with the vanes 31 secured at the periphery of the disk 20. By directing the breeze from the fan at the top or the bottom of the disk, it will be obvious that it is possible to rotate 70 said disk without any difficulty, and by varying the speed of the fan, in the customary manner, the speed of rotation of the disk can likewise be varied.

In all animating members with which I 75 am acquainted prior to my invention, the slots for screens have been made regular with the result that the animating effect is steady and regular, and if such an animating disk were used in connection with the flames 80 indicated, they would have the appearance of always rising to precisely the same height and at the same intervals. Flames, however, do not naturally rise in this manner, and to more perfectly simulate such a rising 85 action, I have devised the novel method, which I preferably carry out by employing such a disk as the disk 20, and forming therein the apertures shown which, while having the same general spiral and radial 90 trend, are extremely irregular in their outlines so that none of them are alike, and more especially is none of them the same as the adjacent apertures. The result of this irregularity is that, with the disk 20 95 rotating at a regular speed, the flames appear to leap up irregularly to different heights, and thus more perfectly simulate the desired aspect.

The poster sheet 15 with the member 16 100 having the aperture 18, and the closely perforated member 17, or the equivalent of these elements, form what I have defined in claim 1 as "a screen member having the animated portion thereof outlined by perforations 105 therein," and in claims 4, 5 and 6 as a "changeable screen member having the animated portion outlined by apertures through which the light rays can pass."

While I have shown and described my 110 invention as embodied in the form which I at present consider best adapted to carry out its purposes, it will be understood that it is capable of modifications, and that I do not desire to be limited in the interpretation 115 of the following claims, except as may be necessitated by the state of the prior art.

What I claim as new and desire to secure by Letters Patent of the United States is:

1. In an animated sign, the combination 120 with a screen member having the animated portion thereof outlined by perforations therein, of a light back of the screen member, an animating member movable between the light and the screen member, said animating member containing a plurality of irregularly shaped apertures therein of different designs elongated substantially at right angles to the line of movement thereof, and means for moving the animating member 125 130

steadily to produce an apparently irregular movement of the animated portion due to the irregular shape of the apertures.

2. In an animated sign, the combination 5 with a casing having a screen member on one side thereof, and a light therein toward the opposite side thereof, of an opaque, circular animating member containing a plurality of consecutively arranged, radially extending, differently shaped light transmitting apertures, each aperture different in shape from the adjacent ones journaled in said casing between the screen member and the light, and means for rotating the animating member steadily for the purpose described.

3. In an animated sign, the combination 20 with a frame, of a changeable poster sheet having a portion adapted to be animated held therein, an opaque screen plate having so much of it as corresponds to the animated portion of the poster sheet cut away, an opaque plate having relatively small, closely spaced perforations therein registering with 25 the cut away part of the screen plate, both of said plates being supported in the frame just back of the poster sheet, a light back of said plates, a member movable between the light and the cut away portion to ani- 30 mate the desired matter, and means to move the member.

4. In an animated sign, the combination 35 with a casing, of a changeable screen member having the animated portion outlined by apertures through which the light rays can pass, a light in the casing back of the apertures in the screen member, an animating member located between the light and the apertures, an adjustable support for the 40 animating member so it can be shifted to co-operate with different parts of the screen

member, and means for moving the animating member in any position to which it may be shifted.

5. In an animated sign, the combination 45 with a casing, of a changeable screen member having the animated portion outlined by apertures through which the light rays can pass, a light in the casing back of the apertures in the screen member, an animating member located between the light and the apertures, an adjustable support for the animating member so it can be shifted to co-operate with different parts of the screen member, and means for moving the animating member in any position to which it may be shifted, said means consisting of a fan 50 adapted to be placed so as to direct a current of air against vanes carried by the animating member.

6. In an animated sign, the combination 55 with a casing, of a changeable screen member having the animated portion outlined by apertures through which the light rays can pass, a light in the casing back of the 60 apertures in the screen member, an animating disk having radially arranged apertures therein and vanes thereon, an adjustable bearing for the animating disk so it can be shifted to co-operate with different parts of 65 the screen member, and an electric fan adapted to be placed in different parts of the casing to direct a current of air against the vanes in any position in which the animating disk may be adjusted.

In witness whereof, I have hereunto set my hand and affixed my seal this 11th day of June, A. D. 1920.

GEORGE R. PYPER. [L. S.]

Witness:

JOHN HOWARD McELROY.
